UNITED STATES PATENT OFFICE.

THOMAS M. BLACKWELL, OF BASIC CITY, VIRGINIA, ASSIGNOR OF ONE-HALF TO
C. H. LAMBERT, OF WAYNESBORO, VIRGINIA.

HINGE.

No. 905,834.

Specification of Letters Patent.

Patented Dec. 8, 1908.

Application filed June 20, 1908. Serial No. 439,601.

To all whom it may concern:

Be it known that I, THOMAS M. BLACKWELL, a citizen of the United States, residing at Basic City, in the county of Augusta and State of Virginia, have invented a new and useful Hinge, of which the following is a specification.

This invention relates to hinges and has for its object to provide a hinge adapted to be secured in place without the use of screws, and to be so applied to the connected parts that the opposed flat surfaces of the latter will come together squarely when the leaves are closed.

It is a well known fact that most hinges now in use especially with those applied to doors that a considerable space exists between the door frame and hinged side of the door when the latter is ajar. The present invention aims to reduce this space to a minimum by so constructing and disposing the hinge upon the connected parts, that when the door is opened the edges of the latter and frame will meet.

Still another object is to provide a hinge exceedingly simple in structure, and comparatively inexpensive to manufacture, and that may be readily applied to connect doors, lids for receptacles articles of furniture and other objects such as an ordinary hinge is used to connect.

With these and other objects in view as will more fully hereinafter appear the present invention consists in certain novel details of construction and arrangement of parts hereinafter fully described illustrated in the accompanying drawings and particularly pointed out in the appended claims, it being understood that various changes in the form proportion, size and minor details of the device may be made without departing from the spirit or sacrificing any of the advantages of the invention.

In the accompanying drawings, Figure 1 is a perspective view of a portion of a door and casing having my improved hinge applied thereto. Fig. 2 is a perspective view of the invention. Fig. 3 is a sectional view taken through a door or casing showing the bed formed for the hinge leaves.

Similar numerals of reference are employed to indicate corresponding parts throughout.

In the construction illustrated, the leaves 1 and 2 are preferably formed of suitable sheet metal and the opposed sides of each

leaf are at one end cut away so as to provide shoulders 3 and 4 which form the inner ends of outwardly and inwardly curved portions constituting beads or ribs 5 and 6 the function of which will appear later. The cut-away end of each leaf is curved outwardly and inwardly forming interlocking knuckles to receive the hinge pintle, the leaf 1 being herein shown having an intermediate cut-away portion so as to provide the end 65 knuckles 7 and 8 and the leaf 2 having cut-away end portions to form an intermediate knuckle 9 adapted to fit between the end knuckles 7 and 8, so that when the pintle 10 has been inserted through the registering 70 openings of the knuckles a complete hinge is formed as illustrated in Figs. 1 and 2.

When the hinge is to be applied to a door or casing as illustrated in Fig. 3, transverse recesses 11, are formed in the opposed faces 75 of the door and frame or other parts to be connected it being designed to have the depth of these recesses slightly greater than the thickness of the hinge leaf and the distance between the sides of said recesses sufficient to form a snug fit for either leaf. If desired the shoulders 3 and 4 may be reduced to a cutting edge, so that when the opposed sides of the parts to be connected are brought together the opening between 80 the floors of the opposed recesses will be sufficient to permit the pintle and reduced portions to be inserted therein until the shoulders 3 and 4 abut against the opposed outer ends of the recesses by now properly 90 covering the outer ends of the lugs in a well known manner the operation of driving the same home may be readily performed, or if preferred the circular seats 12 may be formed at the opposed ends of the recess so that 95 when the opposed sides of the parts to be joined are brought together the hinge may be readily slipped into place.

It can be readily seen with the present construction that sagging of the swinging 100 member will be practically prevented since the weight will not be thrown upon a few screws and it is to be further observed that the parts may be readily detached by simply forcing the swinging member backward 105 when in closed position.

It will be observed by referring to Figs. 1 and 2 that the leaves 1 and 2 are each provided with a central opening 15, for the reception of a small nail or the like by means of 110

which the leaves are held against sliding from the connected parts.

What is claimed is:—

1. A single piece hinge leaf, one end of which is provided with a knuckle, the rear face of the leaf being provided with an integral bead or rib forming an attaching means, and serving to prevent outward displacement of the leaf in the direction of the knuckle.
2. A single piece hinge leaf having a

knuckle at one end, the upper and lower edges of said leaf being turned to form integral attaching beads.

In testimony that I claim the foregoing as my own, I have hereto affixed my signature in the presence of two witnesses.

THOMAS M. BLACKWELL.
